UNITED STATES PATENT OFFICE.

JOHN F. WEDGEWORTH, OF SAREPTA, LOUISIANA.

TIE-PLATE.

1,274,118.

Specification of Letters Patent. Patented July 30, 1918.

Application filed November 21, 1917. Serial No. 203,194.

To all whom it may concern:

Be it known that I, JOHN F. WEDGEWORTH, a citizen of the United States, residing at Sarepta, in the Parish of Webster 5 and State of Louisiana, have invented certain new and useful Improvements in Tie-Plates; and I do hereby declare the following to be a full, clear, and exact description of the invention, such as will enable others 10 skilled in the art to which it appertains to make and use the same.

The object of this invention is to provide a novel form of tie plate designed to be associated with a rail tie formed of wood 15 so as to increase the life of the tie, the said plate being equipped with novel and efficient fastening means for securing a rail to the plate.

Other objects will appear and be better 20 understood from that embodiment of my invention of which the following is a specification, reference being had to the accompanying drawing forming a part thereof, in which:

25 Figure 1 is a fragmentary plan view of one end of a rail tie and a rail, showing the improved plate mounted on the tie for securing the rail in position.

Fig. 2 is a vertical sectional view, taken 30 through Fig 1,

Fig. 3 is a perspective view of the tie plate detached from operative position and with the removable rail-clamping element removed, and

35 Fig. 4 is a perspective view of the removable clamping element detached from operative position.

Referring to the drawing in detail, the letter A designates a rail tie and B one of 40 the rails. Interposed between the upper side of the tie A and resting thereon, and the under side of the base flange of the rail B, is the tie plate 1, which is of rectangular shape and extends longitudinally of the tie 45 A and is provided, adjacent the outer end thereof, with a pair of rail base flange-engaging elements 2, which are arranged in spaced relation and formed integral with the plate 1 and engage over the outer longitudinal edge of the base flange of the rail B, as shown more particularly in Figs. 1 and 2 of the drawing. The outer end of the plate 1 is provided with an opening 3, which extends through the plate and receives the shank of a spike 4, the said shank 50 of the spike 4 being engaged in the tie A

and the flanged head of the spike engages over the outer longitudinal side of the base flange of the rail B, as shown in Fig. 1. The inner end of the plate 1 is provided, 60 adjacent the terminal thereof, with a transversely extending slot 5 that opens into the opposite side edges of the plate and into the upper side of the plate, and the said slot has the side walls thereof undercut, as shown 65 at 6 in Fig. 3 of the drawing. The outer wall of the slot also extends diagonally of the plate 1 throughout the length of the slot. The slot 5 receives an elongated plate 7, which has the opposite longitudinal edges thereof beveled, as at 8, for engaging under the undercut walls 6 of the slot 5, and the said plate has the outer longitudinal edge thereof cut on a diagonal line so as to agree with the outer diagonally extending wall of 75 the slot 5. The plate 7 is provided at a point intermediate its ends with a rail-fastening element 9, which engages over the inner longitudinal side of the base flange of the rail B, as shown in Fig. 2 of the 80 drawing. The plate 7 is also provided on opposite sides of the fastening element 9, and spaced therefrom, with a pair of openings 10, which register when the plate 7 is in operative position, with openings 11 in 85 the lower wall of the slot 5, for the reception of the shanks of a pair of spikes 12, the said shanks of the spikes engaging in the tie body, and the heads of the spikes engaging over the inner longitudinal side of the base 90 flange of the rail B, as shown in Fig. 1. The spikes 12 serve the double function of assisting in holding the rail B against vertical movement and also holding the plate 7 against accidental movement toward the 95 larger end of the slot 5.

It is evident that various changes might be resorted to in the form, construction and arrangement of the several parts without departing from the spirit and scope of the 100 invention as claimed.

Having thus described my invention what I claim as new is:

A rail tie plate consisting of a rectangular body having one end thereof provided 105 with a pair of spaced rail base flange-engaging elements and having a spike-receiving opening located between the rail base flange-engaging elements, the said plate having the other end thereof provided with 110 a groove having one side wall thereof extending diagonally, the lower wall of the

groove having spaced spike-receiving openings therein, an elongated plate removably fitted within the groove in the last-mentioned end of the body and having one side wall thereof extending diagonally and opposing the diagonally extending wall of the groove in the body, the said plate having a pair of spike-receiving openings therein registering with the spike-receiving openings in the lower wall of the groove, and a rail

base flange-engaging element carried by the plate and located between the spike-receiving openings in the plate.

In testimony whereof I affix my signature in presence of two witnesses.

JOHN F. WEDGEWORTH.
